his atty.*

UNITED STATES PATENT OFFICE.

JAMES H. BUNTING, OF NEW YORK, N. Y., ASSIGNOR TO SUSQUEHANNA SILK MILLS, OF NEW YORK, N. Y., A CORPORATION OF NEW YORK.

DESIGN FOR A BROCADE.

52,205.

Specification for Design.

Patented July 23, 1918.

Application filed May 6, 1918. Serial No. 232,953. Term of patent 3½ years.

To all whom it may concern:

Be it known that I, JAMES H. BUNTING, a citizen of the United States, residing at New York city, in the county of New York and State of New York, have invented a new, original, and ornamental Design for Brocades, of which the following is a specification, reference being had therein to the accompanying drawings.

The figure is a plan view of a piece of brocade showing my new design.

I claim:

The ornamental design for a brocade as shown.

In testimony whereof I hereunto affix my signature.

JAMES H. BUNTING.
